B. R. MUDRA

MACHINE FOR CLEANING BALLS

Filed Jan. 14, 1922

WITNESS: Rudolph F. Hlavaty — Bohumil R. Mudra, INVENTOR,

BY

Robert Burns, ATTORNEY.

UNITED STATES PATENT OFFICE.

BOHUMIL R. MUDRA, OF CHICAGO, ILLINOIS.

MACHINE FOR CLEANING BALLS.

Application filed January 14, 1922. Serial No. 529,351.

To all whom it may concern:

Be it known that I, BOHUMIL R. MUDRA, a citizen of the United States of America, residing at Chicago, in the county of Cook and State of Illinois, have invented certain new and useful Improvements in Machines for Cleaning Balls, of which the following is a specification.

This invention relates to machines for cleaning and polishing bowling and like balls, and has for its object:—

To provide a structural formation and association of parts whereby the ball to be cleaned or polished is held in proper position for the action of a power driven concave cleaning head or brush, and in which a turning or shifting of the ball from time to time by the operator can be attained in a ready and convenient manner, all as will hereinafter more fully appear.

In the accompanying drawing:—

Fig. 1, is a vertical sectional elevation of a machine embodying the preferred form of the present improvements.

Fig. 2, is a top view of the same.

Like reference numerals indicate like parts in both views.

Referring to the drawing, 1 designates an upright supporting frame, preferably formed of structural metal rails fixedly secured together and provided intermediate of its height with a floor or platform 2 adapted to support a driving motor 3 usually of the electric type as shown.

4 designates an enclosing shell of an inverted cup form attached at its lower end upon the platform 2 and formed at its upper end with a central bearing hub 5 for the carrying shaft 6 of the rotary cleaning head of the machine.

7 designates a bevel gear wheel secured to the lower end of the shaft 6 in superimposed relation to the motor 3 and having operative engagement with a bevel gear pinion 8 on the armature shaft of said motor to receive positive rotation therefrom.

9 designates the rotary cleaning head mounted on the upper end of the shaft 6 and having its upper face formed with a concave recess adapted to receive a lining 10 of bristles, felt or other usual cleaning or polishing material, with said lining having a concavity corresponding with the con-

vexity of the bowling or like ball to be operated on.

11 designates a skeleton frame pivotally attached to the top of the frame 1 near the rear end of the same by pivot knuckles 12, and having at its front end an operating handle or bail 13 and at its rear end a rearwardly extending arm 14 for connection with a balancing spring 15 or like means arranged intermediate of said arm 14 and the main frame 1 as shown.

16 designates a central ring carried by the skeleton frame 11 and having a diameter a fraction less than that of the ball operated on, so as to form a support for said ball as the same is turned and manipulated at intervals by the operator during the cleaning or polishing operation. In the preferred construction shown in Fig. 1, the supporting ring 16 carries a facing or pads 17 of felt, in order that marring of the ball's surface by contact with the metal of the ring 16 is avoided during the above mentioned turning or shifting manipulation.

Having thus fully described my invention what I claim as new and desire to secure by Letters Patent, is:—

1. In a ball cleaning machine of the type described, the combination of a main frame, a vertical shaft journaled in said frame, means for imparting rotation to said shaft, a cleaning head mounted on the upper end of said shaft and provided with a concave cleaning recess in its upper surface, and an adjustable holding frame having a central ring the orifice of which has a less diameter than that of the ball to be cleaned and adapted to provide a support therefor in the universal turning adjustment of the ball to successively bring the entire periphery thereof in to cleaning contact with the cleaning head.

2. In a ball cleaning machine of the type described, the combination of a main frame, a vertical shaft journaled in said frame, means for imparting rotation to said shaft, a cleaning head mounted on the upper end of said shaft and provided with a concave cleaning recess in its upper surface, and a holding frame pivoted at one side of the main frame and having a central ring the orifice of which has a less diameter than that of the ball to be cleaned and adapted to

provide a support therefor in the universal turning adjustment of the ball to successively bring the entire periphery thereof into cleaning contact with the cleaning head.

- 5 3. In a ball cleaning machine of the type described, the combination of a main frame, a vertical shaft journalled in said frame, means for imparting rotation to said shaft, a cleaning head mounted on the upper end 10 of said shaft and provided with a concave cleaning recess in its upper surface, a holding frame pivoted at one side of the main frame and having a central ring adapted for supporting engagement with a ball to 15 be cleaned or polished, and a balancing means for said holding frame.
4. In a ball cleaning machine of the type described, the combination of a main frame, a vertical shaft journalled in said frame, 20 means for imparting rotation to said shaft, a cleaning head mounted on the upper end of said shaft and provided with a concave cleaning recess in its upper surface, a holding frame pivoted at one side of the main 25 frame and having a central ring adapted for supporting engagement with a ball to be cleaned or polished, and a balancing means for said holding frame, the same comprising a spring connecting a rear extension of said holding frame to the main 30 frame.

5. In a ball cleaning machine of the type described, the combination of a main frame, a motor mounted on said frame, an open 35 bottom shell secured to said frame and enclosing said motor, said shell having a central bearing at top, a vertical shaft journalled in said bearing and operatively connected at its lower end with said motor, 40 and a cleaning head mounted on the upper end of said shaft and formed with a concave cleaning recess in its upper surface.

6. In a ball cleaning machine of the type described, the combination of a main frame, 45 a motor mounted on said frame, an open

bottom shell secured to said frame and enclosing said motor, said shell having a central bearing at top, a vertical shaft journalled in said bearing and operatively connected at its lower end with said motor, a 50 cleaning head mounted on the upper end of said shaft and formed with a concave cleaning recess in its upper surface, and an adjustable holding frame having a central ring adapted for supporting engagement with a ball operated on. 55

7. In a ball cleaning machine of the type described, the combination of a main frame, a motor mounted on said frame, an open bottom shell secured to said frame and enclosing said motor, said shell having a central bearing at top, a vertical shaft journalled in said bearing and operatively connected at its lower end with said motor, a 60 cleaning head mounted on the upper end of said shaft and formed with a concave cleaning recess in its upper surface, and a holding frame pivoted at one side of the main frame and having a central ring adapted for supporting engagement with a ball 65 operated on. 70

8. In a ball cleaning machine of the type described, the combination of a main frame, a motor mounted on said frame, an open bottom shell secured to said frame and enclosing said motor, said shell having a central bearing at top, a vertical shaft journalled in said bearing and operatively connected at its lower end with said motor, a 75 cleaning head mounted on the upper end of said shaft and formed with a concave cleaning recess in its upper surface, a holding frame pivoted at one side of the main frame and having a central ring adapted for supporting engagement with a ball 80 operated on, and a balancing means for said holding frame. 85

Signed at Chicago, Illinois this 31st day of December 1921.

BOHUMIL R. MUDRA.
